UNITED STATES PATENT OFFICE.

HENRY HORAN, OF EAST ORANGE, NEW JERSEY, ASSIGNOR TO HARTFORD CARPET COMPANY, OF HARTFORD, CONNECTICUT.

DESIGN FOR CARPET.

Specification forming part of Design No. **11,371**, dated August 26, 1879; application filed August 2, 1879.
[Term of patent 3½ years.]

To all whom it may concern:

Be it known that I, HENRY HORAN, of East Orange, in the county of Essex and State of New Jersey, have invented a new and original Design for a Carpet, of which the following is a specification.

The accompanying photograph illustrates my new design.

This invention relates to a new design for carpets, oil-cloths, and analogous fabrics; and consists in the novel grouping and configuration of figures, hereinafter more fully pointed out.

The most striking feature of this new design is found in a series of diagonally-placed rectangles, A A, which are all parallel to each other in the carpet, and each of which, at its lower part, has a pointed extension, B, projecting at an angle of about one hundred and thirty-five degrees from the sides of the rect-

angle. These peculiar-shaped figures A B are filled with floral decorations, and also surrounded by a background covered with flowers, as shown.

Lines *a b* extend laterally from the diagonal figures A, indicating, but not completing, further subdivisions of the background, and thereby adding to the novelty of effect produced by the design.

I claim—

1. The design for a carpet, consisting of the figure A B, substantially as shown.
2. The design for a carpet, consisting of the figure A B and lines *a b*, substantially as shown.

HENRY HORAN.
